WET MACHINE AND METHOD

Henri P. L. Laussucq, Reading, Pa., assignor to
Birdsboro Steel Foundry and Machine Company,
Birdsboro, Pa., a corporation of Pennsylvania

Application October 27, 1931, Serial No. 571,345

38 Claims. (Cl. 92—61)

My invention relates to the manufacture of pressed boards from finely divided fiber.

One purpose of my invention is to provide desirable cycles of operation and mechanism adapted to perform the operations.

A further purpose is to vent a press mold in a novel way.

A further purpose is to air vent a press mold through recesses formed in the deckle and to close the recesses by gates.

A further purpose is to adjust the air venting for a press mold during different adjustments of the dies required to press sheets of different thicknesses.

15 A further purpose is to supply end gates through which the mold is filled with fiber, to locate air vent recesses in the deckle sides for venting the interior of the mold as the fiber flows into the mold and close the vent recesses by gates.

20 A further purpose is to vent air from the mold through recesses which extend below the surface of the fiber, whereby excess fiber will flow into the recesses and force the air from the mold through them, and to close the vent recesses by gates after the air has been exhausted from the mold.

A further purpose is to insert relatively large vent recesses within the deckles with the vent inlet openings extending adjacent to the bottom 30 of the mold, to close the recesses by gates and to pass their lower gate edges down into the fiber when the gates are positioned to close the recesses.

A further purpose is to automatically close the vent gates when the material is about to be 35 compressed in the mold by the dies.

A further purpose is simultaneously to operate the flow gates and the vent gates.

A further purpose is to mount the vent gates upon the flow gates.

40 A further purpose is to overfill the mold, to use the movable die to force fiber back through air vent recesses, to stop the die within the fiber in the mold after it has forced the excess fiber from the mold and to close the recesses by vent gates 45 to stop further discharge of the fiber during the compression part of the operation of the dies.

A further purpose is to spray deckle gates with water so as to insure free movement of the gates.

50 A further purpose is to spray water into the vent recesses to keep the recesses open for the free outlet of air from the mold.

A further purpose is to mount the water spray pipes upon the movable deckle and flexibly connect between the spray pipes and a source of 55 supply of water under pressure.

Further purposes will appear in the specification and in the claims.

My invention relates both to the methods or processes involved and to structure by which the methods may be carried out.

I have elected to show one main form only of my invention, selecting a form which is practical and efficient in operation and which well illustrates the principles involved.

Figure 1 is a side elevation of a press, partly in section, embodying my invention.

Figure 2 is a right-hand end view of Figure 1, partially in section on line 2—2 of Figure 1.

Figure 3 is an enlarged fragmentary transverse vertical sectional view also on line 2—2, Figure 1, drawn on a larger scale.

Figure 4 is a longitudinal vertical sectional view on line 4—4, Figure 2, showing the deckle and flow boxes in their lowermost positions, and showing the flow gates closed between the mold and the flow boxes.

Figure 5 is a transverse vertical sectional view as on line 5—5, Figure 4, showing the air vent gates closed between the mold and vent openings in the deckle.

Figure 6 is a view similar to Figure 4, showing the flow gates opened and the mold filled.

Figure 7 is a transverse sectional view on line 7—7, Figure 6, showing the vent gates opened.

Figure 8 is a view similar to Figure 4 showing the flow gates closed and the mold filled.

Figure 9 is a transverse sectional view as on line 9—9, Figure 8, showing the method of spraying or washing the air vent openings and gates.

Figure 10 is a view similar to Figure 4, showing the gates closed and the die lowered and compressing the material into a sheet.

Figure 11 is a transverse sectional view on line 11—11, Figure 10.

Figure 12 is a view corresponding generally to Figure 6 but showing a different filling operation.

Figures 13 and 14 are fragmentary perspective views of structure illustrating my invention.

Like numbers refer to like parts in all figures. Describing in illustration and not in limitation and referring to the drawings:—

Wet machines for forming boards and sheets from paper pulp, leather fiber and other commercial fiber suspensions are well known, and therefore much of the illustration, although showing structure, is to be regarded as conventional. The primary purpose of all such machines is to press liquid, usually water, from raw material suspension to form the raw material into a sheet.

For convenience in designation, I refer to the

raw material, whatever its exact nature, as "finely divided fiber suspended in a liquid" or as "fiber", or "mush", and to the finished product, whatever its dimensions, as a "sheet".

5 Fiber suspensions are difficult to press chiefly because of the extreme readiness with which the fiber precipitates from the liquid. This tendency to precipitate makes it highly important to maintain the fiber flowing continuously in one 10 direction, with as few interruptions as possible, to project the fiber laterally rather than vertically, avoiding sudden dropping into final position, to prevent all escape of liquid suspension medium until precipitation is desired and to charge the 15 mold rapidly and accurately without allowing air to be trapped in the mold.

In the ordinary wet machine the upper die is smooth and the lower die is foraminated for removal of water. This formation gives air access 20 beneath the sheet so that the pressed sheet does not stick nor in many cases fall readily to the lower die but sticks to the upper die where vacuum conditions are created.

While it is customary to construct wet machines with upper movable and lower stationary dies, as illustrated, lower movable dies are sometimes used. It will be evident, of course, that my invention is equally applicable, whether the upper die alone, or the lower die alone, or both dies 30 are movable.

While the upper and lower dies are of course press platens, the term platen is also applied to parts of the press located above or below the movable die, which are used to support the rams.

35 The principal parts of the illustrated wet board press, or wet machine, include top and bottom fixed platens 15 and 16 respectively, and tension columns 17, which form a rigid frame 18. An intermediate movable die or platen 20 and a surrounding movable deckle 21 are slidably mounted upon the columns 17. The intermediate platen 20 is or carries the upper die and the bottom platen 16 is or carries the lower die.

40 The platen 20 is movable to and from the bottom platen 16 by main hydraulic rams 22 operatively mounted in cylinders 23, rigidly secured to the top platen 15. The cylinders 23 have pipe connections 24 through which a pressure medium passes for forcing the rams 22 and the 45 movable die or platen 20 downwardly toward the lower fixed platen 16, which forms the lower die of the press.

45 The movable platen 20 is supported upon and moved upwardly by bars or links 25, connected to the platen 20 and suspended from cross-heads 26, which latter are lifted by retracting rams 27 operating in hydraulic cylinders 28, supplied with fluid through suitable pipe connections 29. The cylinders 28 are rigidly mounted upon pedestals, or bases 30 secured upon the top facing surfaces 50 of lugs 31 forming overhanging portions of the top frame member or fixed platen 15.

55 These are two of the cylinders 28 located at opposite ends of the top platen 15. These cylinders 28 are located upon the longitudinal center line 60 of the platen 15 and centrally of each cross head 26. The cylinders 28 lift the cross heads, which in turn lift the links 25 and the movable platen 20.

65 The movable platen which forms the upper die, is surrounded by a deckle 21, comprising longitudinal sides 32 and 33, located close to the sides of the platen 20. The deckle 21 also includes transverse frame members 34 and 35 rigidly secured to the ends of the sides 32 and 33. Flow boxes 36 and 37 are rigidly connected to the deckle 70 sides at 38 and 39 and to the ends 40 and 41 of

the transverse frame members 34 and 35, which latter form the inner walls of the flow boxes.

80 The deckle sides 32 and 33 carry lugs 42 which are slidably mounted upon the columns 17, thus making the deckle 21 movable relatively to the movable platen 20 and also to the upper and lower dies or platens 15 and 16.

85 The deckle, as formed by the sides 32 and 33 and the end flow boxes 36 and 37, forms a parallelogram defining the sides and ends of the mold. The deckle surrounds the movable platen 20, and these two are moved independently of each other. They form a working fit together, with the result that they move relatively and independently of each other and also form a tight joint for the 90 purpose of sealing the top of the mold.

95 The flow boxes 36 and 37 receive the fiber, mush, or material to be formed into sheets in the press. The mush is supplied to the flow boxes through suitable pipes, not shown in the drawings.

100 The flow boxes 36 and 37 have openings or throats 43 through which the mush flows upon the lower platen 16, filling, or partly filling the mold, or space formed within the deckle when the latter is in its lower position, as shown in the drawings.

105 Mush flow gates 44 are provided upon the deckles to open and close the throats 43 of the flow boxes 36 and 37. Suitable guides, not shown in the drawings, are provided upon the transverse frame members 34 and 35, forming part of the flow boxes, in which guides the mush flow gates 44 are movable vertically.

110 I use the word deckle in its broad sense to mean the lateral wall of the mold, including all inlet gates, vent gates, liners and confining walls whatsoever. I do not regard the distinction between the singular and the plural of the word deckle, nor between the side deckle and the end 115 deckle, as critical.

120 The deckle 21, together with the flow boxes forming part of the deckle, is supported and vertically positioned by hangers 45, having their lower ends rigidly connected at 46 to the transverse frame members 34 and 35, forming the inner walls of the flow boxes. The frame members 34 and 35 are rigidly attached to the end plates 47 of the flow boxes, which plates in turn are rigidly attached to the ends of the deckle sides 32 and 33. 125 The upper ends of the hangers 45 are rigidly secured to the cross heads 48, having their outer ends mounted upon deckle rams 49, operatively mounted in hydraulic cylinders 50 rigidly secured at their lower ends 51 upon extension brackets 52 formed upon the upper platen, or rigid frame member 15.

130 The cylinders 50 are suitably supplied with operating fluid under pressure through pipes 53 so as to lift the deckle 21.

135 The flow gates 44 extend across the full length of the flow boxes 36 and 37. Upon each gate 44, near the center of its length, is secured at 54 an upright or stem 55 having its upper end attached at 56 to a plunger or gate ram 57. There is a 140 plunger 57 for each gate 44.

145 The plungers 57 are operatively mounted in cylinders 58 having fluid connections 59 through which a pressure medium is preferably constantly supplied to the cylinders 58. By this arrangement the flow gates 44 are normally pressed downwardly into the closed position, as shown in Figures 1, 2, 4, 8 and 10 of the drawings. The cylinders 58 carrying the gate rams or plungers 57 are rigidly mounted upon brackets 60, by bolts or tie rods 61. 150

The brackets 60 are mounted upon the cylinders 28.

The flow gates 44 are adapted to be lifted against the heavy downward urging of the constant pressure plungers or rams 57, without lifting the deckle 21, by means of rocker arms 62, which make connection with slotted links 63, shown in dotted lines in Figure 2, by means of pins 64. The lower ends of slotted links 63 make 10 pivotal connections at 65 with the gate upright or stem 55.

The rocker arms 62 are rigidly fastened to a rocker shaft 66, journaled in suitable bearings 67 on the top platen 15, and connected through 15 cranks 68 and connecting links 69 with a horizontal gate-opening ram 70 in a cylinder 71 having fluid connection at 72.

A smaller ram 73, operating in a cylinder 74, with fluid connection at 75, is integral with and 20 opposed to the gate-opening ram 70, and the smaller ram 73, being preferably under constant pressure, heavily retracts the gate-opening ram 70 and thereby rotates the rocker shaft 66 to a position to close the flow gates 44.

25 The slotted link 63 and pin connections at 64 permit upward movement of the deckle 21, including the flow gates 44, as a single unit without changing the positions of the rocker arms 62, and, if the deckle be all the way down, permit opening 30 and closing the flow gates 44 without movement of the deckle. The flow gates 44 lift against the downward pressure of the constant pressure rams 57 by the action of the horizontal gate-opening ram 70 through the rocker shaft 66 and links 63, 35 and close by action of the constant pressure rams 57, upon releasing the horizontal gate-opening ram 70.

When the deckle 21 is raised, the flow gates 44 are kept closed under the heavy downward push by 40 the constant pressure rams 57. The constant pressure ram 73 returns the rocker mechanism to the position of gate closing when the gates are closed by the constant pressure rams 57.

The bottom fixed platen 16 carries a filter bed 45 permitting easy downward drainage or expression of water from the fiber or mush.

As illustrated, in Figures 2 and 5, the top surface of the bottom platen 16 contains a series of transverse drainage grooves 76. The grooved top 50 surface of the platen is covered by a foraminated plate 77, which is in turn covered by a movable screen, or wire, 78 having a mesh of the order of 40 or 60 mesh, desirably shifted and washed after forming each sheet. The shifting and washing are well known in the art.

To avoid uneven stratification or distribution of fiber in the mold and to avoid premature felting of the parts of the body prior to felting of the content in its entirety seepage or leakage of water 60 through the bottom of the mold must be prevented until the pressing operation begins. The water lock upon the bottom of the die 16 therefore retains water in the mold not only while the mush is entering and the mold is filling, but 65 until the die 20 has expelled the air and/or excess mush from the mold and the die 20 is ready to start upon its final downward pressing stroke. The water lock must not open an appreciable length of time before the pressing stroke of the 70 die 20 or it will allow drainage to lower the mush level and thus produce a void which the air will fill; nor should the die 20 start its pressing stroke while the flow gates 44 are open appreciably unless it merely follow up the lowering of the level 75 due to natural drainage.

The water locks illustrated in the drawings comprise vertically sliding valve plates 79 positioned at opposite sides of the lower die 16 close to the ends of the drainage grooves 76, as shown in Figure 7. Troughs 79 are rigidly mounted upon 80 the opposite sides of the die 16 and receive the water from the grooves 76 when the gates are in the lower, or open position.

The sliding plates 79, as shown in Figure 2, are normally held in the raised, or closed position, 85 by weighted arms 80 pivoted upon bearings 81 on the lower die 16. Links 82 are provided for pivotally connecting the arms 80 with the plates 79.

The sliding plates 79 are simultaneously opened 90 with the closing of the flow gates 44, by means of flexible members 83 secured to the weighted ends of the arms 80 and wound around drums 84 secured upon the rocker shaft 66, which latter is rotated when the flow gates 44 are closed. The 95 flexible members 83 are guided by pulleys 83'.

The present invention provides vent gates 85 and vent recesses or passageways 86 within the deckle sides 32 and 33. The vent gates 85 and recesses 86 are located centrally of the mold between the end flow gates 44, which latter are located at the opposite ends of the deckle. The inner surfaces of the deckle sides 32 and 33 are grooved to afford vertical guides for the vent 100 gates 85.

The inner surfaces of the vent gates 85 are flush with the inner vertical surfaces of the deckle sides, and the vent gates form a continuation of the vertical walls of the mold.

The movable die 20 fits within the inner surfaces of the vent gates as well as within the inner surfaces of the deckle sides, thus forming tight joints which prevent the escape of the fiber or mush when the die 20 is lowered to compress the material in the mold.

110 The vent recesses 86 have inner openings 87 of sufficient height to extend vertically from the lower face of the die 20, when it is in its raised position, to a point below the level of the upper surface of the finished sheet when compressed as 115 shown in Figure 11.

120 Each of the vent recesses 86, formed in the deckle sides, has an outwardly and upwardly inclined bottom surface 88. The lower edge of each vent gate 85 is provided with a beveled surface 125 so that the gate will form a tight joint when it is moved downwardly to close the vent recess, as shown in Figures 2 and 5. Each vent recess 86 has an outlet 89 located at a higher level than the inlet opening 87 from the mold. Said outlet 130 89 is formed by a wall 90 formed by the deckle side, which wall is in spaced relation with the outer face of the vent gate, thus forming a pocket or recess into which the fiber may flow when the vent gate is opened, and over the top 135 of which wall 90 the fiber must flow to pass through the outlet 89, as shown in Figure 7.

140 The fiber flows into the mold from the flow gates 44 located at opposite ends of the mold, thus gradually filling the mold. When the two 145 quantities of fiber, flowing from the opposite flow gates, meet in the central portion of the mold the air is forced from the mold through the vent recesses 86. The fiber flows into the vent recesses partially filling the pockets or recesses 86 and 145 thereby forcing the air out through the vent recesses in advance of the fiber so that the latter may entirely fill the mold.

150 By forming the inlet openings 87 of the vent recesses of full height equal to the movement of

the die 20, the vent apertures will allow the air to escape at any level within the limits of the vertical inlet openings 87 thus providing means for venting the mold when filling the mold to any desired level according to the intended thickness of the finished sheet.

When the mold is filled with fiber, the vent gates 85 are lowered to the position shown in Figures 2 and 5 for preventing further escape of the material from the mold. The vent gates 85 and the flow gates 44 are simultaneously closed before the die 20 starts to compress the material in the mold.

Each vent gate 85 is provided with a hanger bar 91 extending in opposite directions from the vent gate. The opposite ends of each hanger bar 91 are supported upon the ends of the flow gates 44. The hanger bars are provided with upwardly and inwardly turned hooks 92, which project over the flow gates, as shown in Figures 1 and 13. By this arrangement the vent gates 85 are raised and lowered simultaneously with the raising and lowering of the flow gates 44.

Overflow pipes 93 are secured upon the deckle sides 32 and 33, and project horizontally from the deckle. The inner ends of the pipes 93 communicate with the outlets 89 of the vent recesses 86 formed in the deckle sides. Said pipes 93 are movable with the deckle. A downwardly projecting pipe 94 is mounted upon the outer end of each overflow pipe 93 and loosely enters and telescopically moves in a fixed drain pipe 95.

The pipe 94 is provided with a hood 96 which surrounds the fixed drain pipe 95 and forms a sliding joint between the fixed drain pipe and the movable drain pipe.

The overflow pipes 93 carry upwardly projecting pipes 97 having ventilating caps 98 through which the air from the recesses 86 is exhausted. The overflow pipes 93 are provided with downwardly inclined lower walls for the free passage of liquid from the outlets 89 of the vent recesses.

Means are provided for washing the fiber from the vent recesses 86 and also from the vent gates 85, insuring that the gates shall work freely and also insuring an open passageway through the vent recesses. The deckle sides 32 and 33 are provided each with apertures 99 which form spray nozzles for directing streams of water into the lower portions of the pockets or recesses 86 formed between the walls of the deckle and the vent gates.

Supply pipes 100 are mounted upon the deckle, and move vertically with the latter for supplying water to the plurality of apertures or nozzles 99.

Branch supply pipes 101 extend upwardly and over the upper surface of the deckle sides and are provided with spray nozzles 102 for directing a spray of water to the surface of the vent gates 85 where it enters the guide formed in the upper portion of the deckle. A flexible pipe 103 is connected with the water supply pipes 100 and 101 so that the supply pipes may move vertically with the deckle.

The pipe 101 is conveniently provided with apertures corresponding to 102 not only upon the face of the pipe adjoining the gate 85 but upon the opposite face of the pipe where they play into a groove 104 upon and along the adjoining face of the deckle. This groove 104 supplies water along the side faces of the gate 85, part of the supporting guide construction of the end of the gate being grooved for this purpose.

It will thus be seen that water flows upwardly into the bottom of the recess and also downwardly

along the flat outer face and along the ends of the gate to wash out the recess and clear the surface of the gate, carrying the mush which is washed free out along with the water through the outlet opening 89.

80

The operation of my invention is as follows: The die 20 is held in the raised position by the rams, and the deckle is lowered upon the bottom platen, thus forming the mold. The flow gates are normally closed relatively to the deckle by the pressure actuated gate rams, and the vent gates are also lowered to the closed position with the downward movement of the flow gates. Figures 4 and 5 show the flow gates and the vent gates in the closed position, and the die 20 moved downwardly to a stopped position to govern the quantity of fiber which can flow into the mold.

85

Suitable means are provided in the form of vertical adjustable stop shafts 105, shown in Figure 1, for locating the position of the movable die 20 so that the mold will contain a measured quantity of fiber for forming a finished sheet of the desired thickness.

90

Various plans of filling and corresponding die operation are available with the mechanism shown. For example, the die may be set at the predetermined limit of filling from which the pressing action is intended to start; in which case the mush is filled in against it and the air extruded by reason of the displacement of the air by the mush as the filling comes in, after which the inlets and air outlets or vents are closed and the pressing action begins. Some mush will also flow out. Figure 4 shows such a mush accumulation waiting for the gates to open to flow into the mold.

95

The mush charge may be predetermined by flow box capacity, as by an overflow weir 106 (Figure 12) with or without filling against the upper die. The excess mush flows over the weir into the space 107.

100

Where over-filling is practiced, the upper die may be set at the limit of overfilling and the mush may be filled in against it, pushing the air out ahead of the mush and following it out within the recess; after which the movable die is pushed downwardly to the normal filling charge position at which pressing is to begin, extruding mush back into the flow box and into the recess all the while, with possible overflow through outlet 93. 125

The inlet gates and permissibly the air vent are kept open during the short downward movement of the upper die while the over-charge is being expelled. The mush inlet gates and the air vent are closed when, by reason of downward movement of the upper die, the limit of intended charge depth has been reached and the pressing operation is to begin.

110

On the other hand whether it be intended to over-charge or not, the depth of initial filling, either the intended final depth of filling or the over-charge depth, can be determined by the volume of mush in the flow boxes. The height of mush initially will then be determined by the settling depth when the flow gates are open. In Figure 12 the charge is measured in the flow box by pouring the excess over the weir. If this depth be the total depth of intended charge for pressing, the upper die is then brought down against it, expelling the air before the air vent is closed and before or after the flow gates are closed according to whether the flow gates are or are not used as air outlet vents or gates.

130

Where it is intended initially to over-charge with the upper die lifted above the charge position, 150

the depth of over-charge is determined by the quantity of mush in the flow boxes and the flow gates are opened, allowing the mush to flow in and to settle to the predetermined height of over-charge. The upper die is then brought down against the over-charge level of mush, expressing the air through the air vents and the flow gates, after which the die is further dropped or forced downwardly until the over-charge has been 10 pressed through the flow gates and/or air vents.

Overcharge and expression of the over-charge through the flow gates has the advantage of additionally expelling the air either through the vents, if they be left open, or through the flow 15 gates, so that the pressing die has complete contact with the mush at the time the die reaches the upper limit of intended pressing movement. The flow gates (and the air vents also if they have been opened for expression of air and mush) are, 20 of course, closed before the operation begins. The use of the air vents in addition to the flow gates for air outlet gives added opportunity for escape of trapped air.

Where there has been over-charge, the first 25 downward movement of the die 20 after it comes in contact with the overcharge level of the mush, presses some of the excess material along with the air through the vent recesses in the deckle sides, giving opportunity for a more complete 30 venting of the air than would take place if care be taken to prevent expression of anything but air only through the vents.

These features of setting of the head to predetermined heights for filling against the head to 35 normal charge, or filling against the head to an over-charge, affect the character and sequence of the steps performed in the filling and pressing operation and are capable of use with any form of venting, but reach their highest utility in conjunction with a form of vent which acts reliably 40 at any height and which is unaffected by the expression of over-charge.

I have considered it unnecessary to show the considerable variety of stop mechanisms by 45 which the height of the movable die can be predetermined so as to set it at the height at which it will limit the charge to a normal pressing charge or to the height at which it will limit the charge to a predetermined extent of over-charge.

50 The means shown for preliminarily setting the height limits the upper height of movement of the movable die so that instead of lifting to a greater height and then lowering to a stop position the movable die is lifted to the predetermined height at which it will limit the charge to 55 a normal or over-charge quantity as planned. The adjusting screws thread into the upper fixed platen as a nut and engage the upper surface of the upper movable die to limit the upward movement of this upper movable die. They can thus be preliminarily set to any predetermined height of upper die movement and furthermore can be set to one position of upper die movement and then can be reset by forcing the upper die down, 60 for allowing it to come up to a different setting.

The threaded stops are operated by worm wheels upon their upper ends, which wheels are turned by worms 108 mounted upon shaft 109 and capable of being turned by a wrench engaging the end 110. This illustration is intended 70 primarily to satisfy the statutory requirement by showing one form which is capable of variation both preliminarily and during operation, but the character of stop used might be quite different.

75 When the mold is entirely filled below the lower

face of the die 20 the fiber will also flow into and partially fill the pockets formed within the vent recesses. Slight depression of the die until it reaches a position governed by stop shafts 105 will force the excess fiber into the flow boxes and also into the vent recesses, as shown in Figures 80 6 and 7. The flow gates and the vent gates are then closed, as shown in Figures 8 and 9. After closing of the flow box and vent gates as also shown in Figures 8 and 9, the flow boxes may 85 start to fill and the vents will drain. After operation, water is supplied to the spray apertures or nozzles for washing out the vent recesses and also for spraying the upper portion of the vent gates, as shown in Figure 9.

Figures 10 and 11 show the die 20 in its lowest position, in which it has compressed the material to form the finished sheet, by the action of the main rams 22, shown in Figure 1. The flow boxes are also shown in Figure 10 more nearly filled 90 ready for the next cycle.

The drainage grooves formed in the fixed platen were closed by the water locks or sliding plates being in the raised position when the mold was being filled, as shown in Figure 7. When 100 the flow gates and the vent gates were lowered to the closed position shown in Figures 8 and 9, the water locks or plates were lowered or opened, as shown in Figure 9, thus allowing the water to flow from the mold to the drainage grooves and 105 into the drainage troughs. Said water locks or plates are maintained opened during the final pressing of the fiber into the finished sheet, as shown in Figure 11.

When the sheet is finished the deckle is lifted 110 by the deckle rams. The upward movement of the deckle releases the tension upon the flexible member thus allowing the weighted arms to close the water locks or plates.

The die is lifted by the retracting rams to a 115 position which will permit the finished sheet to be removed from the press.

It will be evident that the air vents offer air outlet above the mush whatever the height of mush poured, and may be used for mush outlets whether the mush inlets from the flow box be used for this purpose or not. Their outlets over wall 90 are sufficiently high to prevent waste of mush during normal filling, but permit any 120 quantity of mush to be forced out through them 125 up to the time that the gates 85 are closed, whether the gates 44 be closed or open at that time.

This is advantageous in over-filling operations where it is desired to force the excess mush out 130 through the air vents alone, or through the air vents in conjunction with the filling openings.

Provision of vent openings up to the full height of the filling, as provided by my invention, avoids the trapping of air within the mold which is inevitable where a fixed vent is provided which is below the filling level for some volumes of charge. It will be evident that, in forming a sheet, I 135 spread out the mush into a relatively thin layer, introducing the mush and withdrawing the displaced air and excess mush at an edge of the layer, and then closing the gates to prevent escape of material at the edges when the mush is pressed.

In view of my invention and disclosure variations and modifications to meet individual whim or particular need will doubtless become evident to others skilled in the art, to obtain part or all of the benefits of my invention without copying the structure shown, and I, therefore, claim 145 150

all such in so far as they fall within the reasonable spirit and scope of my invention.

Having thus described my invention, what I claim as new and desire to secure by Letters Patent is:—

1. In a wet machine for making sheets or boards from finely divided fiber, a deckle and upper and lower relatively movable dies forming a mold, said deckle having a passageway formed therein providing an air vent, and a gate arranged for closing the air vent. 80
2. In a wet machine for making sheets or boards from finely divided fabric, a deckle and upper and lower relatively movable dies forming a mold, means for supplying mush to the mold, said deckle having a passageway formed through the same providing an air vent open to the atmosphere, and a gate slidably mounted upon the deckle for closing said passageway. 85
3. In a wet machine, upper and lower relatively movable dies, a deckle forming the vertical walls of a mold, means upon the deckle walls for supplying material to the mold, a deckle wall having an air vent recess formed therein open to the atmosphere, said recess being of sufficient dimensions to receive excess material from the mold, and means upon the deckle for closing said recess. 90
4. In a wet machine, upper and lower relatively movable dies, a deckle surrounding the upper die forming a mold, said deckle having an inlet passageway formed therein through which material is supplied to the mold, said deckle having an air vent passageway formed therein located at a remote portion of the mold from said inlet, and gates operatively mounted upon the deckle arranged for closing said inlet and vent passageways. 95
5. In a wet machine, upper and lower relatively movable dies, a deckle having vertical walls surrounding the upper die forming a mold, means upon the deckle for supplying material to the mold, a deckle wall having a vent recess formed therein, said recess communicating with the mold adjacent to the lower face of the upper die when the latter is in its lowest position, and a gate movably mounted upon the deckle arranged for closing communication between the mold and said recess. 100
6. In a wet machine, upper and lower relatively movable dies, a deckle having vertical walls surrounding the upper die forming a mold, means upon the deckle for supplying material to the mold, a deckle wall having a vent recess formed therein, said vent recess forming an opening communicating with the mold coextensive in height with the vertical movement of the lower face of the upper die, and a gate upon the deckle arranged for closing communication between the mold and said recess. 105
7. In a wet machine, upper and lower relatively movable dies, a deckle having vertical walls surrounding the upper die forming a mold, means upon the deckle for supplying material to the mold, a deckle wall having a vent recess formed therein, said recess registering with the mold throughout the entire distance traversed by the lower face of the upper die during the opening and closing movements of the latter, and means upon the deckle arranged for closing said recess. 110
8. In a wet machine, upper and lower relatively movable dies, a deckle having vertical walls surrounding the upper die forming a mold, means upon the deckle for supplying material to the mold, a deckle wall having a vent recess formed therein, said recess having a relatively large inlet passageway from the mold forming a pocket into which excess material may enter from the mold, and a gate movably mounted upon the deckle positioned between the vertical face of the upper die and the deckle wall, arranged for closing the passageway between the mold and said recess. 115
9. In a wet machine, upper and lower relatively movable dies, a deckle having vertical walls surrounding the upper die forming a mold, means upon the deckle for supplying material to the mold, a deckle wall having a vent recess formed therein, said deckle wall having an upwardly and outwardly inclined discharge wall defining said recess, and a gate movably mounted upon the deckle, positioned upon the inner vertical face of the deckle for closing the passageway between the mold and said recess. 120
10. In a wet machine, upper and lower relatively movable dies, a deckle having vertical walls surrounding the upper die forming a mold, means upon the deckle for supplying material to the mold, a deckle wall having a vent recess formed therein, said deckle wall having an upwardly and outwardly inclined wall defining said recess, a gate slidably mounted upon the deckle, and said gate having a beveled lower edge surface corresponding to the inclined surface of the wall forming said recess arranged for closing communication between the mold and said recess. 125
11. In a wet machine, upper and lower relatively movable dies, a deckle having vertical walls surrounding the upper die forming a mold, means upon the deckle for supplying material to the mold, a deckle wall having a vent recess formed therein, said recess forming an upwardly and outwardly extending diagonal passageway through the deckle wall communicating at its inner end with the mold when the upper die is in its lower position and having its outlet positioned adjacent to the level of the lower face of the upper die when the latter is in its raised position, and a gate movably mounted upon the deckle arranged for closing communication between the mold and said recess. 130
12. In a wet machine, upper and lower relatively movable dies, a deckle having vertical walls surrounding the upper die forming a mold, means upon the deckle for supplying material to the mold, a deckle wall having a vent recess forming therein, said recess communicating with the mold at a level to receive material from the mold, an overflow pipe upon the deckle communicating with said recess adjacent to the level of the upper portion of the mold, and means for closing communication from the mold through the recess. 135
13. In a wet machine, upper and lower relatively movable dies, a deckle having vertical walls surrounding the upper die forming a mold, means upon the deckle for supplying material to the mold, a deckle wall having a vent recess formed therein, said recess communicating with the mold at a level to receive material from the mold, an overflow pipe mounted upon the deckle and connected with said recess adjacent to the level of the upper portion of the mold, a vertically positioned branch pipe mounted upon said overflow pipe and a drain pipe with which said branch pipe is slidably connected. 140
14. In a wet machine, upper and lower relatively movable dies, a deckle having vertical walls surrounding the upper die forming a mold, means upon the deckle for supplying material to the mold, a deckle wall having a vent recess formed therein, an overflow pipe having an air ventilat- 145
- 76

ing outlet, a branch pipe mounted upon said overflow pipe, a vertically positioned drain pipe into which the end of the branch pipe loosely enters, and a hood upon said branch pipe loosely embracing the drain pipe.

15. In a wet machine, upper and lower relatively movable dies, a deckle surrounding the upper die forming a mold, said deckle movably mounted relatively to said dies, a flow box upon the deckle for filling the mold with fiber, a gate arranged for closing the flow box, said deckle having an air vent recess formed therein communicating with the mold, a gate arranged for closing communication between the air vent recess and the mold, an overflow pipe mounted upon the movable deckle and connected with said recess, an upwardly extending air vent pipe upon said overflow pipe, a drain pipe, and a telescoping connection between said overflow pipe and the drain pipe.

20. In a wet machine, upper and lower relatively movable dies, a deckle surrounding the upper die forming a mold, said deckle movably mounted relatively to said dies, a flow box upon the deckle for filling the mold with fiber, a gate arranged for closing the flow box, said deckle having an air vent recess formed therein, a gate arranged for closing communication between the air vent recess and the mold, and means for simultaneously opening and closing said gates.

25. In a wet machine, upper and lower relatively movable dies, a deckle surrounding the upper die forming a mold, said deckle movably mounted relatively to said dies, a flow box upon the deckle for filling the mold with fiber, a gate arranged for closing the flow box, said deckle having an air vent recess formed therein, a gate arranged for closing communication between the air vent recess and the mold, means for raising and lowering the flow box gate, and means for mounting the gate controlling the air vent recess upon the flow box gate.

30. In a wet machine, upper and lower relatively movable dies, a deckle surrounding the upper die forming a mold, said deckle movably mounted relatively to said dies, flow boxes located upon opposite ends of the deckle for filling the mold with fiber, gates arranged between the flow boxes and the mold, said deckle having air vent recesses formed in the side members thereof, gates upon the deckle arranged for controlling communication through said air vent recesses, hanger bars upon which the gates controlling the air vent recesses are mounted, said hanger bars supported at their opposite ends upon the flow box gates, and means for raising and lowering the flow box gates.

35. In a wet machine, upper and lower relatively movable dies, a deckle surrounding the upper die forming a mold, said deckle movably mounted relative to said dies, flow boxes located upon opposite ends of the deckle for filling the mold with fiber, gates arranged between the flow boxes and the mold, said deckle having air vent recesses formed in the side members thereof, gates upon the deckle arranged for controlling communication through the air vent recesses, hanger bars upon which the gates controlling the air vent recesses are mounted, hooks formed upon the opposite ends of said hanger bars, said hooks being supported upon the flow box gates, and means for raising and lowering the flow box gates.

40. In a wet machine, walls forming a mold, gates in the vertical mold walls moving in guide-

ways and means for applying water to the guideways for flushing and lubricating the gates.

45. In a wet machine, upper and lower relatively movable dies, a deckle surrounding the upper die forming a mold, said deckle having a vent passageway formed through the vertical wall thereof communicating with the mold, a gate movably mounted upon the deckle for closing said passageway, and a water supply pipe upon the deckle having an outlet located adjacent to the gate arranged for flushing the latter.

50. In a wet machine, upper and lower relatively movable dies, a deckle surrounding the upper die forming a mold, said deckle movably mounted relatively to the dies, said deckle having an air vent recess formed therein, a gate slidably mounted upon the deckle arranged for closing communication between the mold and said air vent recess, and a spray nozzle mounted upon the deckle arranged for spraying the surface of the gate which is presented toward said recess formed in the deckle.

55. In a wet machine, upper and lower relatively movable dies, a deckle forming the vertical walls of a mold having a vent passageway through the vertical wall of the deckle, a gate slidably mounted upon the deckle arranged for opening and closing said passageway, and a water supply pipe having an outlet located upon the deckle arranged for spraying the surface of the gate which is in sliding contact with the deckle.

60. In a wet machine, upper and lower relatively movable dies, a deckle forming the vertical walls of a mold having a vent passageway through the vertical wall of the deckle, a gate slidably mounted upon the deckle arranged for opening and closing said passageway, and a water supply pipe connected with said deckle, said deckle having a spray aperture formed therein communicating at one end with said water pipe and at its other end with said passageway.

65. In a wet machine, upper and lower relatively movable dies, a deckle forming the vertical walls of a mold, said deckle having a vent passageway formed therethrough, a gate slidably mounted upon the deckle arranged for opening and closing said passageway, a water pipe having an outlet located above the deckle for spraying the surface of the gate which is in sliding contact with the deckle, a second water pipe leading into said passageway adjacent to the outer surface of the gate, a water supply pipe, and a flexible pipe-connection between said water pipes and said supply pipe permitting the free movement of the water pipes with the deckle.

70. In a wet machine, upper and lower relatively movable dies, a deckle forming the vertical walls of a mold with which said dies are operatively associated, walls forming a vent recess through the deckle providing a passageway communicating with the mold, a gate slidably mounted in the deckle and positioned vertically between the deckle and the upper movable die, said deckle having an outwardly and upwardly inclined wall defining said recess, said wall having an aperture formed through the same communicating with said recess between said wall and the outer surface of the gate relatively to the mold, and a water supply pipe connected with the deckle and communicating with said aperture for spraying the surface of the gate and said recess.

75. A wet machine having an air outlet permitting overflow of mush in a vertical wall of the mold, a closure for said opening and spray means for cleaning the closure and outlet.

28. A wet machine having an air outlet permitting overflow of mush in a vertical wall of the mold, a closure for said opening and spray means for cleaning the outlet. 80
- 5 29. A wet machine having an air outlet from a vertical wall of the mold permitting flow of mush therethrough and walls forming a pocket communicating with said outlet and having an overflow weir in combination with spray means for cleaning the pocket. 85
- 10 30. A wet machine having inlet and air vent outlet openings and concurrently operated separate closure means for the two openings. 90
- 15 31. In a wet machine having inlet and air vent openings and a water lock controlling the passage of liquid through the filter bed, means for closing the inlet and air outlet openings and concurrently operated means for opening the water lock when the inlet and air outlet are closed. 95
- 20 32. In a wet machine having inlet and air vent openings and a water lock controlling the passage of liquid through the filter bed, means for closing the inlet and air outlet openings and concurrently operated means for closing the water lock when the inlet and air outlet are opened. 100
- 25 33. The method of forming a sheet of material from mush, which consists in spreading out the mush within a closed space into a relatively thin horizontal layer, introducing the mush to the layer at one edge and forcing the air displaced by the mush and the excess mush out at another edge, in completely enclosing the sides of the layer while maintaining the space occupied by the layer constant and in subsequently compressing the layer to remove liquid from the mush. 105
- 30 34. The method of forming a sheet of material from mush, which consists in spreading out the mush within a closed space into a relatively thin horizontal rectangular layer, in introducing the mush at an edge of the layer, in a direction diagonal of the layer and forcing out the air and excess mush at an adjacent edge of the layer, in 110
